UNITED STATES PATENT OFFICE.

EDGAR L. WORK, OF COLUMBUS, OHIO, ASSIGNOR OF ONE-THIRD TO FRANK J. WILLIAMS, OF COLUMBUS, OHIO.

WELDER'S FACE SHIELD.

Application filed June 22, 1920. Serial No. 390,934.

To all whom it may concern:

Be it known that EDGAR L. WORK, a citizen of the United States, residing at Columbus, in the county of Franklin and State of 5 Ohio, has invented certain new and useful Improvements in Welders' Face Shields, of which the following is a specification.

This invention relates to improvements in face shields for arc welders, and has for 10 its primary object to provide a face shield of strong, substantial and durable construction and which is adapted to be supported from the hand of the user when actively employed in shielding the face.

15 Another object of the invention resides in a welder's face shield which is formed essentially from a single blank of fibrous material, said blank being cut and bent in a peculiar manner so that the body produced thereby will be of hollow pyramidal form, and to provide in conjunction with the smaller end of the body a vision frame which contains a substantially translucent panel and by means of which more or less 20 restricted vision through the shield is obtainable.

A further object of the invention resides in forming the vision frame in such manner that the transparent or translucent panel 25 positioned therein may be readily removed from its applied or operative position and yet when within the frame, means are provided for retaining the panel in a secured and positive manner and free from the possibility of accidental displacement.

A still further object of the invention resides in providing said frame with a depending stud, to which is vertically secured a hollow handle member, the latter serving 40 to provide means whereby the shield as a whole may be conveniently gripped by the user and held in such manner as to effectually shield the face and yet to allow freedom of manipulation on the part of the 45 shield.

With these and other objects in view, as will appear as the description proceeds, the invention accordingly consists in the novel features of construction, combinations of 50 elements and arrangements of parts, herein-after to be fully described and pointed out in the appended claim.

In the accompanying drawings, forming

a part of this specification, and in which similar characters of reference denote like 55 and corresponding parts throughout the several views thereof:

Figure 1 is a plan view of the material blank from which the body of the shield comprising the present invention is formed, 60

Figure 2 is a perspective view of the improved shield comprising the present invention in its completed form,

Figure 3 is a horizontal sectional view taken through the shield, and 65

Figure 4 is a vertical sectional view.

As is well understood, it is imperative in the art of electric welding that means be provided for protecting the face and more particularly the eyes of the operatives engaged in such work, inasmuch as the arc produced in electric welding is of a very blinding character and since the operator is obliged to closely view the work in which he is engaged it is necessary that his eyes 75 should be protected from the glare created by the arc and also from flying particles which are incident to the task of welding. The present invention, therefore, provides 80 a shield particularly adapted for this purpose, and one which is light in weight, easy to manipulate and of such character as to thoroughly protect the face of the user.

To this end, my improved shield is formed to comprise a hollow substantially frusto-pyramidal shaped body 1. This body is preferably formed from a sheet of fibrous material so as to possess lightness in weight 85 considerable strength and durability and to act as an insulator against the passage of electrical current. As shown in Figure 1, this body is formed from a single blank of sheet material, which blank is substantially hexagonal in form and has a substantially triangular portion 2 cut out thereof to produce the outwardly diverging edges 3. Also, the central portion of the blank is cut out to produce a central opening 4, the function of which will develop hereinafter. The outer margins of the body 1 after the elimination of the portion 2, produce a five sided figure, and the edges of the openings 4 are 90 also similarly shaped to conform relatively in position and length to said outer edges.

After the formation of the blank thus described the body may be slightly damped 95 100 105

by being left in a relatively moist place which renders the body more or less plastic and capable of being bent. When the desired degree of plasticity has been reached 5 the blank is folded along the dotted lines disclosed in Figure 1 until the edges 3 are arranged in parallel overlapping relations, whereby by so bending and drawing the blank a body will be produced of substantially hollow frusto-pyramidal formation, which will be of sufficient area and proportions to encase the face and to thereby protect the latter in a manner to be hereinafter fully developed. The edges 3 are united and rigidly secured by passing rivets or the like 6 therethrough, in order that the rivets may be interiorly clinched so as to hold said edges together and thereby retain the permanent form of the body 1. 15 When the edges 3 are secured together in the manner above related the opening 4 will be of substantially rectangular configuration and to the edges of this opening a metallic frame 9 is secured. As shown 20 in Figures 3 and 4 the frame is formed to comprise a marginal flange 10, which is riveted or otherwise secured as at 11 to the margins of the opening 4, hence, through the provision of the rivets 11 or their equivalents 25 the frame 9 will be permanently secured to the body 1 in contiguous relationship with the opening 4. The frame is provided interiorly with a lens chamber 12 having inwardly projecting and spaced side 30 walls 13 and a surrounding outer wall 14, the side walls 13 being relatively narrow in order that the same will not obstruct vision through the opening 4 or through the frame 9 generally. Positioned within the chamber 12 is a translucent lens or vision plate 15, which is preferably formed from darkly colored glass and by being of this formation the same will serve to effectively preclude the injurious rays emitting from the 35 welding operation from injurious contacting or engaging the eyes of the user. 40 The panel or plate 15 is removably received within the chamber 12. This is accomplished by forming another of the outer 45 walls 14 of the chamber with slots 16 through which the plate 15 may be passed when being positioned into or removed from the chamber. Then, to prevent accidental removal or dislocation on the part of the 50 plate, said chamber is provided with one or more leaf springs 17 which press centrally upon the upper and lower edges of the plate 15 and thereby serve to force the latter normally into seated engagement with the inner of the side walls 13. However, 55 when it is desired to remove the panel 15, pressure is applied from the inside of the shield, which has the effect of compressing the spring 17 so that the panel as a whole 60 may be readily slipped through and out of 65

the slot 16. By virtue of this construction it will be apparent that quick repairs may be made in the shield in the event of injury to the frangible vision plate, and similarly, adjustment may be made by employing 70 panels of varying degrees of transparency and color, in order that the shield may be adapted to suit the particular tastes and requirements of varying users or to varying 75 conditions of use.

The frame is provided in this instance with a depending stud 18 the upper portion of which terminates in an annular shoulder 19. A hollow handle member 20 is adapted 80 to be inserted upon the stud 18 and is forced upwardly upon the latter until its upper edge seats upon the shoulder 19. A rivet or bolt 21 is then passed through the handle and the stud for the purpose of rigidly and firmly securing said handle member in connection 85 with the shield as a whole. The handle member is preferably formed from the same material as the body 1 and hence is a non-conductor of heat and electricity. By its location the handle member may be conveniently 90 grasped by the user so that the shield may be manipulated with a considerable degree of facility and convenience so that the same may be quickly laid aside when not in active 95 use.

In view of the foregoing description and the accompanying drawings it will be apparent to those versed in the art that a face shield has been provided of a practicable, efficient and substantial nature and one which may be used for a considerable period of service. It will be apparent that the formation of the body 1 from a single blank of sheet material will result in considerable 100 economy from a standpoint of production and that by cutting the blank in the manner described the hollow frusto-pyramidal formation of the body can readily be produced. The removable construction of the lens plate 15 also furnishes another desirable feature 105 in that quick repair and adjustments may be secured. Then, by the provision of the handle 20 all straps and other harness that have been heretofore employed in devices of this character are eliminated, and said 110 handle thus enables the shield to be handled in a practical and convenient manner so that loss of time hitherto largely involved in the use of a face shield will be reduced to a 115 minimum.

In view of the foregoing description it is thought that the operation and construction of the present invention will be readily understood by those skilled in the art, and therefore a more extended explanation has 120 been accordingly omitted.

What is claimed is:

A method for producing welders' face shields which consists in utilizing a single 125 piece blank of pliable material cutting 130

blank so as to provide a triangular slot and a central five sided opening, the sides of the opening corresponding in number with the side edges of the blank, folding the blank

5 so that the side edges of the triangular slot are brought into parallel overlapping relationship and securing them at the overlapped

points to hold the entire body in substantially pyramidal formation and with the side edges of the central opening in rigid angular 10 relation.

In testimony whereof I affix my signature.

EDGAR L. WORK.
